D12-44. OR D 2,312 EX.

142312
Albert Bridges Design for Bucket
Patented May 15, 1866

The City of New York, N.Y.

Letter Patent No. 121,412, dated Nov. 15, 1876.

Design for Bracket.

The schedule referred to in these letters is intended making part of the same
full when it may come.

Be it known that I, Albert Bridgeman, of the City
and County of New York, in the State of New York, have invented or produced
a new and original design for a bracket intended more especially for
hanging luggage over the heads of passenger cars in railroads cars;
and I do hereby declare that the following is a full and exact description
of the same.

The accompanying drawing forms a part of this specification,
and is a side view of a bracket constructed according to my design and
erected in place as is as.

A is the ridge of the roof of the car. The bracket is
curved to be parallel to the points indicated by arrows.

B is the ridge. Carrying scroll below it is a branching
scroll which is divided into four branches D' E' F' G'. The scroll is
curved to be parallel to the connection of the branch D' by a connection
at d. The scroll B is connected to the branch D' by a chain
imitation of an old. This chain leads from near the end of the scroll D'
and a bend, as represented.

The curved chain or imitation chain E, extends from the
connection of the scroll B across the entire bracket, and terminates at the connection
of the scroll B, in addition to those before enumerated, or represented
at f' and g'.

2

Des. 2312

The additional features of my design, the bracket and
etc are sufficiently indicated by the drawing alone without descriptive
language. I prefer to make the bracket according to my design on cast
iron, bronze, or brass.

Having now fully described my design, what I claim
as my invention and desire to secure by Letters Patent is The general con-

figuration of the parts as represented and described forming a new design
for a bracket.
